ROTATABLE WINDOW STRUCTURE

Regenald H. Smith, St. Albans, N. Y.

Application October 1, 1946, Serial No. 700,394

6 Claims. (Cl. 20—51)

1

The present invention is directed to window structures, more particularly to a construction which will allow windows to be replaced and to be conveniently cleaned and repaired.

The usual window as heretofore used consists of a frame within which are mounted a pair of window sashes containing one or more panes of glass in each sash and capable of being raised or lowered. If it is necessary to replace a pane of glass, the worker is required to work from the outside, usually on a ladder and under considerable difficulties in order to replace the same. Also, if cleaning of the window is in order, it is most difficult to clean the outer surface of the glass and here also it is usually necessary for the worker to operate from the outside. Whether a ladder is used or whether a safety belt is employed by the worker, the cleaning of the outside of the window introduces an element of difficulty and danger. A similar situation applies where it is desired to introduce screens for the window or storm sash at appropriate seasons of the year.

The present invention is intended and adapted to overcome the difficulties and disadvantages inherent in prior structures of the type described, it being among the objects of the present invention to provide a window structure having certain removable elements whereby access to the outer face of the window may be readily obtained from the inside.

It is also among the objects of the present invention to provide a window structure wherein the entire window as a unit may be readily removed from the window opening or frame so as to allow access for bringing into the structure or removing therefrom, bulky articles such as pianos, furniture, and the like.

It is further among the objects of the present invention to provide a window structure wherein storm sash and/or screens may be readily introduced or removed.

It is still further among the objects of the present invention to provide a window structure wherein one or more panes of glass may be removed from the sash for replacement purposes from the inside of the structure.

Other objects of the invention will appear in the following specification, among which are relative simplicity of structure, ease of operation and adaptability to quantity production with fireproofing materials.

In practicing the present invention, there is provided the usual opening which constitutes a frame fixed in the building structure. Mounted in the opening is a casing with means for mount-

2

ing the window sash therein. The casing is in two parts which meet along diagonal lines, one of said parts being fixed in the frame and the other part being hinged thereto. The sash is mounted on the hinged part and means are provided for locking the casing in fixed or operative position. By this arrangement, the entire window as a single unit may be swung inwardly to provide a free opening which is substantially the size of the window frame. With such a large opening, it is a simple matter to introduce into the structure or remove therefrom, bulky furniture, machines and manufactured goods.

Preferably the window sash is not mounted directly in the casing but there is provided a sash frame which has pivot members on the top and bottom, said pivots being held in bearing members formed in the corresponding parts of the casing. The lateral edges of the sash frame are flattened and bevelled so as to allow rotation thereof with respect to the casing, without interference and yet allowing relatively close fit between the casing and sash frame. Felt or similar members are provided at the meeting edges of casing and sash frame so as to provide a weather-proof joint without interfering with the rotational movements of the sash frame.

Within the sash frame is a plurality of windows separate therefrom. Each window consists of a pane of glass or other transparent material surrounded by a rim or border of a suitable configuration in order that the same may lock into the sash frame. Such locking arrangement is so constructed that after the window is fitted into the sash, a weather-proof joint is obtained. There is further provided in the sash frame a plurality of sashes usually in two sets. The first set consists of an upper and a lower sash fitting into grooves in the sash frame and capable of vertical movement therein. The second set is similarly mounted in a position parallel to the first set. The windows are removably held in the respective sashes.

By such an arrangement, many advantages are obtained in that when it is desired to clean a window, it is merely necessary to rotate the sash frame until the outside of the glass is accessible from the inside; thus the operation of cleaning becomes a very simple matter. A similar situation applies when it is necessary or desirable to introduce storm windows or screens. The inner set of window sashes is raised or lowered so as to give access to the outer set. Then by a simple unlatched operation, the outer window is removed and replaced by a screen or vice versa. When it

is desired to repair any of the window panes, it is merely necessary to unlatch the same and to replace it. All of this work may be accomplished from the inside of the structure.

The arrangement contemplates a window construction which may be produced of any suitable construction materials including metal. It is quite simple to include or otherwise form each of the parts of the arrangement from light metals, plastics or the like, and then assemble the several elements. This greatly reduces the cost of production, makes for greater beauty, more permanence and ease of maintenance.

In the accompanying drawings constituting a part hereof, and in which like reference characters indicate like parts,

Fig. 1 is a front elevational view of a window structure made in accordance with the present invention, the view being taken from the inside of the structure;

Fig. 2 is a rear elevational view of the structure shown in Fig. 1, showing the outside of the window and illustrating screens in place thereon;

Fig. 3 is a perspective view of the casing constituting an essential part of the structure, said casing being shown separate from the remainder of the window;

Fig. 4 is a perspective view of the sash frame which normally fits into the casing of Fig. 3, said sash frame being also shown detached from the other elements of the structure;

Fig. 5 is a perspective view of one of the sash frames, illustrating the locking of the window therein;

Fig. 6 is a vertical cross-sectional view through the central portion of the new window structure and taken along the line 6—6 of Fig. 1;

Fig. 7 is a horizontal cross-sectional view taken along the line 7—7 of Fig. 1 and showing the window in its normal operative position;

Fig. 8 is a view similar to Fig. 7, showing the sash frame rotated into the position 90° to the plane of the window to give access to the outside thereof;

Fig. 9 is a view similar to Fig. 7, some parts being broken away for clearness and showing the manner in which the casing may be rotated to expose the full opening of the window;

Fig. 10 is a fragmentary perspective view of one of the window sashes, illustrating the manner in which it is locked into the sash frame;

Fig. 11 is a fragmentary cross-sectional view in substantially enlarged form, being a cross-section taken along the line 11—11 of Fig. 8;

Fig. 12 is a view similar to Fig. 11 but is taken along the line 12—12 of Fig. 9;

Fig. 13 is a fragmentary perspective view of a sash and window, showing the manner in which the two are interlocked to form a weather-proof joint;

Fig. 14 is an enlarged horizontal cross-sectional view taken through the lower edge of a sash and showing the locking arrangement whereby the window is held in the sash, and

Fig. 15 is an enlarged fragmentary cross-sectional view showing a guiding device for insuring that the two parts of the casing assume the proper position when locked together.

With reference to the drawings, there is provided an opening or window frame 1 which constitutes the frame into which the new window structure is mounted. There is provided a casing consisting of two parts 2 and 3 which are complementary and which fit together to form a rectangular casing. This is fitted into frame 1.

Within said casing is a sash frame 4 which is rectangular and which fits into the opening of the casing. At least one pair of sashes 5 carrying windows 6 are mounted in sash frame 4.

Referring particularly to Fig. 3, the casing has side members 7 and 8 in vertical and parallel relation to upper members 9 and 9', respectively. Lower members 10 and 10', respectively, complete the structure of the casing. A hinge 11 is provided along the front of member 7 and screws 12 hold the same with relation to frame 1. Screws 13 are provided in elements 9' and 10' to fix the right hand section permanently into frame 1. An opening 15 is provided into which a pin or other latching device 16 may be introduced. The left hand part of said casing is free to pivot on hinge 11, whereby elements 7, 9 and 10 carrying parts described below, may be swung inwardly to free the opening in frame 1.

20 In the upper face of member 10 is a circular depression 17 constituting a bearing. In the upper face of member 9 there is a similar recess 18 and an opening 19 centrally thereof extends through member 9. Members 9 and 10 meet members 9' and 10', respectively, along a broken, split line, consisting of a diagonal line 20 at a proper angle to the plane of the window and a second line 21 at an angle to line 20. A recess 22 at the junction of lines 20 and 21 carries a latch 23 held by screw 24 in frame 1 to allow the same to be rotated. Extensions 25 are provided thereon to provide means for grasping the same with the fingers for rotation of latch 23. When the latch is in the position shown in Figs. 8 and 35 11, it prevents movement of one part of the casing relative to the other. When the latch is in the position shown in Figs. 9 and 12, the left hand side of the casing is free and it may be swung into positions as shown in Fig. 9.

40 With particular reference to Fig. 4, the sash frame 4 consists of vertical members 26 and 27, the outer sides of which are flat and the front and rear edges of which are beveled to provide flat portions 28. The bottom 29 and top 30 of the sash frame have their outer surfaces flat so as to fit closely to the inner surfaces of the corresponding members of casing 2 and 3. The top of member 30 is provided with a stub shaft 31 having a boss or bearing 32 fixed to the top thereof. Said stub 31 is adapted to fit into opening 19 and boss 32 is adapted to rest upon recess 18. The lower face of member 29 is provided with a projection 33, as shown in Fig. 6, fitting into recess 17. Thus elements 32 and 33 45 constitute a pivot about which sash frame 4 may be rotated. Strips 34 and 35 of felt or other weather-proof material is cemented or otherwise secured to the inner faces 36 of members 7 and 8. Edge surfaces 28 of sash frame 4 are adapted to contact with said strips when the sash frame is in closed or operative position. Faces 36 are curved, the curvature being with the axis of frame 4 as a center to prevent interference with the movement of said frame.

50 At line 20 in member 9, there is provided a pin 37 which extends into an opening 38 in member 9'. This constitutes a guide so that as the casing is swung into closed position, the several parts thereof will properly fit together.

55 This insures proper locking of the casing in position. Sets of grooves 39 and 40 are provided in sash frame 4 for the reception of window sashes. An opening 49 in alignment with opening 15 passes through bottom member 29. Pin 16 shown in Fig. 6 is adapted to pass through

openings 41 and 15 to lock frame 4 in position. Each of the windows 6 is provided with a glass pane 42 held in place by putty 43 or the like. The outer edges of window 6 are provided with shoulder portions 44 which are complementary and are adapted to fit into corresponding shoulders 45 in sash frame 5. The upper edges of window 6 are also formed with shoulder portions 46 adapted to fit into corresponding and complementary portions 47 in the sash frame, as shown in Figs. 6 and 10. A rib 48 on the top of window 6 is adapted to fit into groove 49 in sash frame 5.

A latch is mounted in the bottom of window 6 consisting of a bar 50 having a pivot 51 integral therewith, the latter fitting into window 6. Bar 50 carries a short flat handle 52. A circular opening 53 is provided in sash 5, said opening cutting through the front of said sash. A recess 54 in the front of sash 5 communicates with opening 53. When window 6 is placed in position, rib or tongue 48 is first moved into position in groove 49 and the window is then swung about said tongue, causing bar 50 to pass into opening 53. Then handle 52 is moved to the left into closed position as shown at 55' in Fig. 14.

A guard 56 is provided along the upper edge of sash frame 4, being secured thereto at the outside of said frame and extending downwardly to cover the upper part of sash frame 5 as shown in Fig. 2, thus protecting the upper end against the entrance of rain, snow or the like. Along the bottom of sash frame 4 is a guard 57 having an inwardly turned portion 58 bearing against the lower edge of sash frame 5. This completes the protection against entrance of water.

Although the invention has been described setting forth a single specific embodiment thereof, the invention is not limited to the exact details of construction as many changes in the details may be made within the spirit of the invention. For instance, the pivoting of sash frame 4 need not be in a vertical axis but the axis may be in other positions such as horizontal. In Fig. 6 there has been shown a pair of windows 6 on the inside of the structure and a pair of screens on the outside. There may be more than one pane of glass in each window and screens may be omitted and replaced by window glass, or only one of the sets of sashes may be used at any one time. It is not necessary that all of the elements of the invention be incorporated in a single window structure as some of the elements may be used independently of others, as for example, sash frame 4 may be made rotatable as shown, but the casing may have the hinge omitted or the reverse structure may be utilized. The various means for fixing the several elements relative to other elements do not constitute an essential part of the invention as equivalent means are well known and may be used in place thereof. Several latching arrangements may be replaced by others suitable for the purpose.

In place of felt strips 34 and 35, other weather-proofing material may be used, such as vulcanized soft or hard rubber, spring metal, or the like. Said strips are shown attached to members 7 and 8, but one or both strips of each pair may be attached to surfaces 28; or a different type of weatherproofing may be resorted to. For ventilation purposes, one of the windows of each pair, such as the upper inner and the lower out-

er window, or vice versa, may be replaced by screens; thereby, when all the window sashes are locked ventilation is obtained, which is a considerable advantage as during rain-storms or when the occupants are temporarily away, adequate circulation of air is obtainable. Also, all four windows shown in Fig. 6 may be of glass, in which case they provide double or storm windows for winter weather, while at the same time allowing all of the windows to be moved to provide ventilation.

These and other changes in the details of the construction of the present invention may be made within the principles herein set forth and the invention is, therefore, to be broadly construed and not to be limited except by the character of the claims appended hereto.

I claim:

1. A window comprising a window-frame adapted to be fixed in a structure, a casing fitted in said frame and hinged thereto at one side, the top and bottom of said casing being split along a vertical plane adjacent the other side thereof, said other side being fixed to said window-frame, a sash-frame fitted in said casing and having top and bottom pivots in its vertical centerline, the bottom pivot inserted in a recess in the bottom of said hinged casing, the top pivot passing through a shouldered opening in the top of said hinged casing and constituting a bearing for said sash-frame, and window sashes in said sash-frame.

2. A window comprising a window-frame adapted to be fixed in a structure, a casing fitted in said frame and hinged thereto at one side, the top and bottom of said casing being split along a vertical plane adjacent the other side thereof, said other side being fixed to said window-frame, a sash-frame fitted in said casing and having top and bottom pivots in its vertical centerline, the bottom pivot inserted in a recess in the bottom of said hinged casing, the top pivot passing through a shouldered opening in the top of said hinged casing and constituting a bearing for said sash-frame, the sides of said casing being curved on an arc having said centerline as a center, the sides of said sash-frame being flat with beveled edges, and window sashes in said sash-frame.

3. A window comprising a window-frame adapted to be fixed in a structure, a casing fitted in said frame and hinged thereto at one side, the top and bottom of said casing being split along a vertical plane adjacent the other side thereof, said other side being fixed to said window-frame, a sash-frame fitted in said casing and having top and bottom pivots in its vertical centerline, the bottom pivot inserted in a recess in the bottom of said hinged casing, the top pivot passing through a shouldered opening in the top of said hinged casing and constituting a bearing for said sash-frame, the sides of said casing being curved on an arc having said centerline as a center, the sides of said sash-frame being flat with beveled edges, vertical weather-stripping along the edges of said casing sides adapted to contact with said beveled edges to form a weatherproof joint, and window sashes in said sash-frame.

4. In a window having a casing adapted to be fixed in a structure and a sash-frame fitted in said casing and having top and bottom pivots in its vertical centerline, the bottom pivot inserted in a recess in the bottom of said casing, a shouldered opening in the top of said casing

and constituting a bearing for said sash-frame, said top pivot having a boss at its upper end, said boss bearing upon the shoulder of said opening, whereby said sash-frame is suspended from above, and window sashes in said sash-frame.

5. In a window having a casing adapted to be fixed in a structure and a sash-frame fitted in said casing and having top and bottom pivots in its vertical centerline, the bottom pivot inserted in a recess in the bottom of said casing, a shouldered opening in the top of said casing and constituting a bearing for said sash-frame, said top pivot having a boss at its upper end, said boss bearing upon the shoulder of said opening, whereby said sash-frame is suspended from above, the sides of said casing being curved on an arc having said centerline as a center, the sides of said sash-frame being flat with beveled edges, and window sashes in said sash-frame.

6. In a window having a casing adapted to be fixed in a structure and a sash-frame fitted in said casing and having top and bottom pivots in its vertical centerline, the bottom pivot inserted in a recess in the bottom of said casing, a shouldered opening in the top of said casing and constituting a bearing for said sash-frame, said top pivot having a boss at its upper end, said boss bearing upon the shoulder of said opening, whereby said sash-frame is suspended from above, the sides of said casing being curved on

10 5 an arc having said centerline as a center, the sides of said sash-frame being flat with beveled edges, vertical weather-stripping along the edges of said casing sides adapted to contact with said beveled edges to form a weatherproof joint, and window sashes in said sash-frame.
